UNITED STATES PATENT OFFICE.

GABRIEL FELSENTHAL, OF CHICAGO, ILLINOIS.

PICTURE-FRAME.

1,253,803.

Specification of Letters Patent. Patented Jan. 15, 1918.

Application filed October 9, 1917. Serial No. 195,551.

To all whom it may concern:

Be it known that I, GABRIEL FELSENTHAL, a citizen of the United States, and resident of Chicago, county of Cook, and State of Illinois, have invented certain new and useful Improvements in Picture-Frames, of which the following is a specification, and which are illustrated in the accompanying drawings, forming a part thereof.

10 The invention relates to picture frames and more particularly to those having a front face of celluloid or similar flexible material requiring a stiff metal backing throughout a substantial portion of its entire area. The object of the invention is to provide an attractive picture frame of durable but inexpensive construction and affording an efficient protection for the contained picture. To this end the invention 15 contemplates a construction wherein the celluloid front and its metal backing are permanently associated while still permitting the contained picture to be removably held in face contact with the said celluloid front.

20 In the accompanying drawings:

Figure 1 is a front elevation of the improved picture frame, some parts being broken away to show the form of the several parts and the manner in which they are assembled,

Fig. 2 is a vertical sectional view taken centrally through the frame, and

Figs. 3 and 4 are perspective views showing the metal backing or shell separated from other parts and a removable back piece, respectively.

In carrying out the invention a sheet metal plate 10 of substantially the size and shape of the completed frame is provided. 40 This plate is centrally apertured at 11 in accordance with the size and shape of the picture, as 12, to be shown and it is preferably pressed to a curved form for imparting a somewhat bulging or convex contour 45 to the front face 13 of the frame. The front face 13 comprises a continuous imperforate sheet of celluloid or similar flexible material. This sheet is stretched over the front of the metal plate 10 and these two parts 50 are permanently united continuously along their entire margins, as at 14, by crimping the parts together in the manner well understood by those familiar with the working of these materials. As a celluloid sheet 55 requires a metal backing throughout a substantial portion of the sheet, the central

opening 11 of the plate 10 is relatively small and a wide margin 15 is provided about the contained picture, as 12.

While that part of the front face 13 which extends over the opening 11 is desirably transparent, the remainder of the sheet may be ornamented by any desired method but it is preferably rendered opaque for the purpose of concealing the metal plate 10. The drawings show a sheet 16 of ornamented paper permanently adhering to the front face 13 upon the inside of the same. The sheet 16 is centrally apertured to provide an opening 17 which registers with but is preferably slightly smaller than the opening of the plate 10.

The frame is most readily completed by applying a thick sheet 18 of a soft book binder's board or the like to the rear face of the metal plate 10. The sheet 18 may be held in place by being pressed against the rear face of the metal plate 10 within the crimped margin 14 of the frame. The introduction of the picture 12 is permitted by forming the sheet 18 with a central opening 19 of the full size of the picture and, preferably somewhat larger than the central opening 11 of the metal plate 10. A plug 20 removably filling the opening 19 serves for holding the picture flat against the transparent portion of the front face 13. If the plug 20 comprises that part of the sheet 18 which is removed by punching the opening 19 it will fit the said opening sufficiently tight to firmly hold the picture 12 in place and to insure against accidental removal of the plug.

When the frame is to be used as an easel, a folding leg 21 may be provided. As shown, this leg is applied to the plug 20. A cord 22 for suspending the frame may also be supported, as by being attached to the sheet 18 above the opening 19. A finger hole 23 to facilitate the removal of the plug 20 is provided if the margin of the plug is notched, as at 24 (Fig. 4).

I claim as my invention:

1. A picture frame comprising, in combination, an integral flexible celluloid disk 105 comprising a marginal portion of substantial width and a transparent portion located centrally within the said marginal portion, a centrally apertured stiff sheet metal shell 110 forming a backing for the celluloid disk throughout its entire extent except at its said transparent portion, the edges of the said

disk and shell being interfolded continuously about the said disk and shell, and a removable pressure plate for holding a picture in face contact with the said transparent portion of the celluloid disk upon the inside of the same through the shell aperture.

2. A picture frame comprising, in combination, an integral flexible celluloid disk comprising a marginal portion of substantial width and a transparent portion located centrally within the said marginal portion, a centrally apertured stiff sheet metal shell forming a backing for the celluloid disk throughout its entire extent except at its said transparent portion, the edges of the said disk and shell being interfolded continuously about the said disk and shell, forming a rearwardly projecting marginal flange, a relatively thick centrally apertured board fitting within the said flange and frictionally held thereby in face contact with the inside of the shell and a notched plug fitting the aperture of the board and removably held therein by frictional engagement of its rim with the margin of the board aperture, the said plug constituting a pressure plate for holding a picture in face contact with the said transparent portion of the celluloid disk upon the inside of the same

through the shell aperture and the notch of the plug providing a finger hole for removal of the plug.

3. A picture frame comprising, in combination, an integral flexible celluloid disk comprising a marginal portion of substantial width and a transparent portion located centrally within the said marginal portion, a centrally apertured stiff sheet metal shell forming a backing for the celluloid disk throughout its entire extent except at its said transparent portion, the edges of the said disk and shell being interfolded continuously about the said disk and shell, forming a rearwardly projecting marginal flange, a relatively thick centrally apertured board fitting within the said flange and frictionally held thereby in face contact with the inside of the shell and a plug fitting the aperture of the board and removably held therein by frictional engagement of its rim with the margin of the board aperture, the said plug constituting a pressure plate for holding a picture in face contact with the said transparent portion of the celluloid disk upon the inside of the same through the shell aperture.
